UNITED STATES PATENT OFFICE.

GUSTAF CARLSON, OF DE KALB, ILLINOIS.

FOLDING UMBRELLA.

974,643.

Specification of Letters Patent.

Patented Nov. 1, 1910.

Application filed January 25, 1910. Serial No. 540,024.

To all whom it may concern:

Be it known that I, GUSTAF CARLSON, a subject of the King of Sweden, residing at De Kalb, in the county of DeKalb and State of Illinois, have invented new and useful Improvements in Folding Umbrellas, of which the following is a specification.

This invention relates to improvements in folding umbrellas and has for its object the provision of a device of that kind which may be raised and lowered the same as an ordinary umbrella when in use and folded into a comparatively small compass when not in use.

Another object is the provision of a folding umbrella provided with a plurality of rib sections and a connection between said rib sections, whereby the latter are fixedly held in axial alignment with each other when the umbrella is in use and yieldingly held parallel with each other when the device is folded.

A still further object is the provision of a construction which will not materially increase the cost of manufacture of devices of this kind and will present no unsightly appearance when in use.

With these and other objects in view, which will more fully hereinafter appear, the present invention consists in certain novel details of construction and arrangement of parts, hereinafter fully described, illustrated in the accompanying drawings and more particularly pointed out in the appended claims; it being understood that various changes in the form, proportion, size, and minor details of the device may be made, within the scope of the appended claims, without departing from the spirit or sacrificing any of the advantages of the invention.

In the accompanying drawings, forming a part of the specification;—Figure 1 is a side elevation of a portion of an umbrella showing the stick sections partly in section and my improved device in side elevation and connecting the rib sections and stretcher. Fig. 2 is a side elevation of a portion of the stick with the ribs and stretchers folded substantially parallel with each other. Fig. 3 is a similar view showing a pair of ribs completely unfolded and another pair partly unfolded. Fig. 4 is a detail of two of the handle sections partly in longitudinal section and showing a spring member uniting said handle sections, in side elevation.

Fig. 5 is a detail perspective of one of the clips for uniting the coupling plate with one of the rib sections and also an end portion of one of the stretchers and showing the improved device in side elevation and applied to the said rib sections and stretcher. Fig. 6 is a detail side elevation of the device showing the adjacent end portions of the ribs in extended position. Fig. 7 is a plan view of the parts shown in Fig. 6. Fig. 8 is a side elevation of the device showing the ribs partly in section parallel with each other. Fig. 9 is a sectional end elevation on the line 9—9 of Fig. 6.

Similar numerals of reference are employed to designate corresponding parts throughout.

The stick sections are designated by the numerals 5 and 6. The section 5 is provided at one end with a handle 7. The section 5 is tubular and fitted in the end remote from the handle 7 is a tubular section 8, one end of which extends in advance of the adjacent end of the section 5. The opposite handle section 6 is tubular and of a size to receive the tubular member 8 carried by the section 5 as clearly shown in Fig. 4. The sections 5 and 6 are held together by means of a spring member. This member includes an elongated bowed shank portion 9 one end of which is fixedly secured in the tubular member 8, while its opposite end is provided with a lateral lug 10 which extends through a lateral opening in that portion of the tubular member extending in advance of the handle section 5. A similar lug 11 extends from the spring member and is arranged between the shank 9 and lug 10. This lug 11 extends through a lateral opening formed in the tubular member 8 and also through an alining opening formed in the section 5 and constitutes a thumb piece. The end of the section 6 which receives the projecting end of the tubular member 8 is provided with an elongated slot, which receives the lug 10 at one end of the spring member when the parts are in position as shown in Figs. 1 and 4. By virtue of the lug 10 entering the slot in the stick section 6, it will be evident that the sections will be united and so held until the spring member is moved inwardly by bearing on the thumb piece 11, whereupon the lug 10 will be moved from engagement with the stick section 6 whereupon the stick sections may be separated.

Fixedly secured adjacent to that end of the

stick section 6 opposite to the end which receives the tubular member 8 is a grooved collar 12, to which is pivotally secured the inner ends of a plurality of inner rib sections 13. The rib sections 13 are of the usual type and are substantially U-shaped in cross section.

The runner 14 is slidingly fitted on the stick sections and at one end is provided 10 with a grooved collar 15 to which is pivoted the inner ends of a plurality of stretchers 16. The stick section 6 is provided with the usual spring latch 17, adapted to engage with the runner 14, when the latter is raised 15 to prevent downward movement of the runner and support the device in raised position. The outer rib sections are designated by the numeral 18 and secured to both the outer and inner rib sections is the usual 20 cover 19.

The device forming the subject matter of the present invention is employed to connect the adjacent ends of the rib sections 13 and 18 and also the outer ends of the stretchers 25 of the said rib sections. By reference now to Figs. 1 to 3 inclusive and also 6 to 9 inclusive it will be seen that fixedly secured to the adjacent ends of the rib sections 18 are what will subsequently be termed a pair 30 of clips 20 and 21. These members are preferably formed of single pieces of sheet metal oblong in contour and bent into substantially a U-shape, whereby sides 22 and 23 are provided as clearly shown in Figs. 5 35 and 9. The sides 22 and 23 terminate at one end in widened portions 24 and 25, these widened portions extending in advance of the adjacent ends of the rib sections. Formed integrally with the sides 22 and 23 are lugs 40 26 and 27 and since the sides 22 and 23 are of such width when the clips straddle the rib sections the edges of these sides will be in alignment with the sides of the rib sections. Bending the lugs 26 and 27 downwardly 45 and over the opposed inner faces of the sides of the rib sections will secure the clips thereto. The inner ends of the enlarged portions 24 and 25 are provided with lateral ears 28 and 29. These ears receive the opposite terminals of a pair of helical retractile springs 30 and 31, the function of which will appear later.

The coupling plate is designated by the 55 numeral 32 and is preferably formed of a single piece of sheet metal oblong in contour and rectangular in cross section and considerably less in thickness than the space between the sides of the rib sections 13 and 18. Formed in the medial portion of one side of the coupling plate 32 is an inwardly 60 extending recess 33, the width of which corresponds approximately to one-fourth the length of the plate and formed in that side 65 of the plate in which the recess 33 is formed

and located between the opposite ends of the plate are a pair of inwardly extending recesses 34 and 35 corresponding in width approximately to the width of the recess 33 but considerably less in depth than the latter. By virtue of these recesses, it will be evident that projections will be formed on one side of the plate, the projections on either side of the recess 33 constituting lugs 36 and 37 while those at the outer ends of the recesses 34 and 35 constitute stops 38 and 39. The lugs 36 and 37 are insertible between the widened portions 24 and 25 of the clips and are pivoted therebetween by means of pivot pins 40 extending through 70 alining openings formed in the widened portions 24 and 25 and arranged above the ears 28 and 29, the said pivot pins also extending through openings in the lugs 36 and 37. The clips are so positioned on the lugs that 75 their adjacent ends will lie comparatively close to each other when the clips extend parallel with the coupling plate as clearly shown in Figs. 1, 3, 6 and 7. When the parts are in these last-named positions the 80 stops 38 and 39 will enter between the side walls of the ribs and bear on the said ribs, whereby the ribs will be prevented from movement in one direction. It will be observed when the stops engage with the ribs 90 that the springs 30 and 31 by virtue of their location below the pivotal points of the clips 95 will tend to hold the ribs and stops in close engagement.

Extending downwardly from the corners 100 of the coupling plates underlying the outer ends of the inner rib sections 13 are bracket arms 41. Connection between these bracket arms and the runner 14 is established by means of the stretchers 16, the opposite ends 105 of which are pivoted to the runner as before described and to the bracket arms 41.

Having now described the construction of the device its operation will be given:— Assuming that the ribs and stretchers are in 110 position shown to be the right in Fig. 1 and it is desired to fold the device the outer rib sections are first moved upwardly against the action of the springs 30 and 31, to positions at substantially right angles to the 115 inner rib sections, as clearly shown on the right of Fig. 3. When the parts are so positioned the runner is moved upwardly on the stick sections and beyond the latch 17 and to a point adjacent to the grooved collar 12. When the parts are in these positions the outer sections 18 are moved inwardly and parallel with the inner sections 13. It will be observed, by reference to Fig. 3, at 120 the beginning of the folding movement, that is when the outer sections 18 are bent at right angles to the inner sections 13, that end of the coupling plate in engagement with the outer ends of the inner rib sections 125 13 will be moved outwardly from the said 130

rib sections and the springs 30 and 31 will extend in a plane oblique to the length of the coupling plate, as clearly shown in Fig. 3. Thus it will be seen when the outer sections are moved parallel with the inner sections as before described the distance between the lugs 28 and 29 to which the terminals of the springs are secured, will be decreased whereupon the tension of the 10 springs will be reduced and since the lugs on both clips will now be in a common plane and it being understood that the springs will be sufficiently tensioned to hold the outer rib sections against outward movement 15 it will be evident that the ribs will be yieldingly held in folded position. When it is desired to open the parts from the position shown in Fig. 2 to that shown in Figs. 1 and 3 the runner is moved downwardly 20 to the lowest point on the stick section 5 after which the outer rib sections may be moved downwardly and in axial alinement with the inner rib sections. It will be observed when the rib sections are unfolded, 5 and the springs 30 and 31 tensioned as before described the frame may be raised and lowered in the ordinary manner without danger of the rib sections folding.

From the foregoing it can be seen that I have provided a device which is comparatively simple in structure and inexpensive in manufacture, and which may be applied to most forms of umbrellas now in use without necessitating any expensive alterations 5 in the same.

I claim:—

1. In a folding umbrella, an oblong coupling plate provided on one side and adjacent to its opposite ends with lugs, a rib

section provided at one end with a channeled 40 clip to receive one of said lugs, and a pivot pin passing through the said clip and lug, a second rib section forming a continuation of the first-named rib section, said second rib section having at one end thereof a channeled 45 clip similar to the first-named clip and pivotally connected to the other of said lugs, laterally disposed lugs arranged on said clips and located to one side of the pivotal connection between said clips and coupling 50 plate, and a spring having its opposite terminals secured to said lugs, for the purpose described.

2. In a folding umbrella, an oblong coupling plate provided on one side and adjacent to its opposite ends with lugs, a rib section provided at one end with a channeled 55 clip to receive one of said lugs, and a pivot pin passing through said clip and lug, a second rib section forming a continuation of the first-named rib section, said second rib section having at one end thereof a channeled 60 clip similar to the first-named clip and pivotally connected to the other of said lugs, laterally disposed lugs arranged on said clips 65 and located to one side of the pivotal connection between said clips and coupling plate, a spring having its opposite terminals secured to said lugs, and stops arranged on said coupling plate and beyond said lugs to limit 70 the pivotal movement of the rib sections.

In testimony whereof I affix my signature in presence of two witnesses.

GUST. CARLSON.
